TO CHARLES E. WARE.

SAFETY STOP-MOTION FOR SPEEDER-MACHINES.

1,354,070.

Specification of Letters Patent.

Patented Sept. 28, 1920.

Application filed August 7, 1919. Serial No. 315,933.

To all whom it may concern:

Be it known that I, WALTER F. TRAYWICK, a citizen of the United States, residing at Belmont, in the county of Gaston and State 5 of North Carolina, have invented certain new and useful Improvements in Safety Stop-Motions for Speeder-Machines; and I do declare the following to be a full, clear, and exact description of the invention, such 10 as will enable others skilled in the art to which it appertains to make and use the same.

This invention relates to safety stop motions for speeder machines.

15 The primary object of the invention is to provide a means for automatically stopping a speeder machine when one of the cone belts breaks and causes the respective lower cone to drop, thus preventing the yarn from 20 breaking and tangling.

Another object of the invention is to generally improve upon devices of this nature by the provision of a comparatively simple, strong, durable and inexpensive construction, one which will be efficient and reliable 25 in operation, and well adapted to the purpose for which it is designed.

With these and other objects in view, the invention consists of certain novel features 30 of construction, and the combination and arrangement of parts as will be hereinafter fully described and claimed.

In the accompanying drawings in which 35 similar reference characters designate like parts throughout the several views,

Figure 1 is a conventional representation of a speeder machine, showing a device constructed in accordance with this invention applied thereto, said device being in set 40 position, and

Fig. 2 is a similar view of a machine showing the device in actuated position.

Referring more particularly to the drawings, the numeral 1 designates the upper 45 cone of a speeder machine, 2 the lower cone thereof which is driven from the upper cone by means of a belt 3. In order to maintain the belt 3 at all times tight, the cone 2 is more or less supported by the belt so that 50 in case of the breakage of the belt, the cone 2 will drop. The cone 1 is driven, the power being supplied to the entire machine by means of a belt 4 which engages a guide

pulley 5. When the machine is not in operation, the belt 4 is shifted from the drive 55 pulley 5 to an idle pulley 6 by means of a belt shifting rod 7. The parts just described are all old in practically all types of speeder machines, and hence form no part of the present invention. 60

The improved stop motion consists of a lever 8 which is fulcrumed intermediate of its ends as at 9 to a stationary part of the speeder machine. The upper end of the lever 9 is forked as at 10 and this forked 65 portion straddles the rod 7 and engages a collar 11 carried by the rod so as to shift the latter when said lever is rocked. The lower end of the lever 8 is pivotally connected to one end of a bar 12 which will 70 hereinafter be referred to as a trigger. The other end of the trigger 12 is bent laterally as at 13, and the free end of this laterally bent portion carries an arm 14 which engages a resilient brake bar 15 to hold the 75 same out of engagement with a pulley 16 carried by the shaft of the upper cone. A coil spring 17 connected at one end to the brake bar 15 and at its other end to the floor or other stationary part of the machine exerts its tension so as to move the brake bar 15 into frictional engagement 80 with the pulley 16 when the arm 14 is disengaged from the bar 15.

Screwed or otherwise fixed to the floor or 85 other movable part of the speeder machine is a bracket 18, the latter forming a support for a lever 19 which is fulcrumed intermediate of its ends and provided at one end with a post 20 disposed directly beneath the 90 lower cone 2 so as to be engaged by the cone when the same drops. The other end of the lever 19 carries a plate 21 having a guide opening 22 therein to receive and guide the trigger 12, and a hook-shaped lug 95 or arm 23 positioned so as to engage a stop 24 fixed to the floor of the speeder machine and thereby limit the movement of the lever. The trigger 12 is provided with a notch 25 which is adapted to engage the 100 stop 24 and hold said trigger in set position against the tension of a spring 26 connected at one end to the trigger and at its other end to the floor of the machine.

When the machine is running, the normal 105 position of the parts of the stop motion is in-

dicated in Fig. 1 of the drawings. By this it will be seen that the lever 19 having the trigger 12 resting upon and slidably connected to one end is over-balanced at this end so that the trigger also rests upon the stop 24 with its notch 25 engaged with the stop and the spring 26 being under considerable tension. The arm 14 is also in engagement with the brake bar 15 holding it out of engagement with the pulley 16 and putting the spring 17 under tension. Should the belt 3 break, the cone 2 will necessarily drop to the position shown in Fig. 2 of the drawings and engage the post 20. The weight of the cone 15 resting upon the lever 19 will overbalance the weight carried at the other end of said lever and bring the same to its other position. This movement raises the trigger 12 so that its notch 25 is disengaged from the stop 24. The trigger 12 is then free to slide and such a motion takes place under the pressure of the spring 26. When the trigger 12 slides, the lever 8 is necessarily rocked and the movement of this lever shifts the rod 7 so as to shift the belt 4 from the drive pulley 5 to the idle pulley 6. Power is thus removed from the machine. When the trigger 12 is shifted the arm 14 carried by the same will slide from under the bar 15, and the latter will be moved into engagement with the pulley 16 under the action of its spring 17. The motion of the cone 1 will therefore be immediately arrested, and the yarn contained on this and the other cone 2 will not be subjected to being broken or tangled. The machine cannot be started until the belt 3 is mended or replaced by a new belt and the stopping mechanism set in the position shown in Fig. 1.

40 The trigger 12 is provided with a notch 27 adapted to engage the stop 24 and hold the trigger in released position. There may be times when such a locking means is desirable.

45 From the foregoing description taken in connection with the accompanying drawings, the construction, use and operation of the invention will be readily understood.

Various changes in form, proportion and in the minor details of construction may be 50 resorted to without departing from the spirit

of the invention as defined in the appended claims.

What is claimed is:

1. The combination with a speeder machine, of a lever fulcrumed to a stationary part of the machine and operatively connected to the belt shifting rod thereof, a brake for one of the upper cones of the machine, a stop fixed to a stationary part of the machine, a trigger connected to said lever and engageable with said brake, said trigger being engageable with said stop when in set position to hold said lever and said brake inoperative, and a second lever fulcrumed to a stationary part of the machine and engageable with said trigger to release the latter and permit said first lever and said rod to shift and said brake to be applied, said second lever being positioned beneath and adapted to be engaged by the corresponding lower cone of the machine upon breaking of the belt connecting said cones.

2. The combination with a speeder machine, of a lever fulcrumed to a stationary part of the machine and operatively connected with the belt shifting rod thereof, a brake for one of the upper cones of the machine, a stop fixed to a stationary part of the machine, a second lever fulcrumed to a stationary part of the machine beneath the corresponding lower cone thereof and carrying a guide and a lug at one of its ends, said lug being positioned for engagement with said stop when said second lever is in one of its positions, a slidable trigger extending through said guide and having one end connected to said first lever, said trigger engaging said stop when in set position, an arm carried by said trigger and when the latter is in set position engaging said brake to hold the same inoperative, a spring for applying said brake when released, and another spring connected to said trigger for shifting the same, the first lever and said belt shifting rod when said trigger is moved out of engagement with said stop by the second lever.

In testimony whereof I have hereunto set my hand.

WALTER F. TRAYWICK
